UNITED STATES PATENT OFFICE.

HILDING LUBECK, OF HESERUD, SWEDEN.

HEATING ARRANGEMENT FOR ROOMS AND THE LIKE.

1,391,745.

Specification of Letters Patent. Patented Sept. 27, 1921.

Application filed February 4, 1919. Serial No. 274,990.

To all whom it may concern:

Be it known that I, HILDING LUBECK, a subject of the King of Sweden, residing at Heserud, Sweden, (at present at Biltmore 5 Hotel, New York city, N. Y.) has invented certain new and useful Improvements in Heating Arrangements for Rooms and the like, of which the following is a specification.

This invention relates to heating arrangements for rooms and the like, more particularly to a heating system in which radiators are employed to heat the rooms. The object of my invention is to provide a new form of radiator and a novel arrangement of the 10 same in the room, which will in many respects be superior to the radiators commonly used at present.

These radiators, in their present form, must, from an esthetic point of view, be considered very unsatisfactory. The otherwise good appearance of a room is often spoiled to a large extent by these radiators. Furthermore, owing to their construction and shape, they are very difficult to keep free 20 from dust and dirt, and therefore they are also unsatisfactory from a hygienic point of view.

In order to improve the appearance of a room, attempts have been made to hide these 30 radiators from view, by building some kind of a cupboard or like covering around them, with openings for the escape of the heat. While this may in a way fulfil its purpose as regards appearance, it must be considered 35 even more unsatisfactory from the hygienic point of view.

Radiators made in accordance with my invention are both from the esthetic and from the hygienic point of view much superior to 40 the previously used radiators, inasmuch as the new radiators will not differ noticeably in appearance from ordinary skirting boards, and through their shape and arrangement they do not form accumulating places for 45 dirt and dust; besides, they can be cleaned just as readily as ordinary skirting boards. A further advantage of my new radiators over previously known types resides in the fact that the heat will radiate from a point 50 close to the floor surface of the room, and is therefore well utilized. Another important advantage is that, owing to my new radiator arrangement, the heat will be distributed through the room quite evenly, thus 55 insuring a comfortable heat in the room.

In the accompanying drawings I have illustrated my new radiator construction, and its installation in a room, Figure 1 being a vertical section through a room, with my radiators applied, and Fig. 2 showing, 60 in a horizontal section, certain details to be described presently.

In Fig. 1, A indicates the floor of the room, B one of the walls, and C another wall transverse to the wall B and showing also a 65 door frame D. Arranged along the walls B and C are the radiators, formed of two vertically-extending spaced walls E, E', connected at their bottom by a preferably horizontal section E''. The wall E of the radiator is preferably in contact with the wall (B or C) of the room, and the front wall E' 70 of the radiator is formed at its upper end with a rearwardly-inclined portion E*, which is joined with the upper end of the rear wall 75 E. The wall portion E* is preferably given an ornamental shape so that it will, together with the front wall E', have the appearance of an ordinary skirting board.

The radiators are preferably made of sheet 80 metal, for instance by first suitably shaping them in a rolling mill to the desired profile, and then bending the sheets to the box-like shape and making a tight joint between the two walls, as by welding or soldering their 85 edges together. Such skirting board radiators, particularly if made of sheet metal, may be constructed in certain desired lengths, to suit different requirements. They may of course be constructed in any other suitable 90 way, as for instance by casting. The radiators may, if desired, be secured to the walls of the rooms in any suitable manner. (Not shown.)

In installing my radiator system, I preferably arrange the radiator sections along the walls, wherever convenient, and where the wall is interrupted, as for instance by a door, as shown at D, I connect the sections on both sides of the door by pipes F, preferably arranged in the floor, and covered by a protecting board G on top of which may be located a portion of the threshold H of wood or metal. In order to allow the pipes to be readily connected with the 105 radiator sections, the latter extend preferably for a certain distance into the floor, as shown.

In some cases it may not be possible, owing to the shape of the room, to provide 110

skirting board radiators all along the walls, or this may not be desirable for other reasons. In order to preserve in such a case the uniform appearance of the room, I may 5 arrange in the spaces between the radiator sections proper, panels I, as shown at the left-hand side of Fig. 1, and also in section in Fig. 2, the panels I being provided, as shown in this latter view, in the corner C'' 10 of the wall C'; the panels I would preferably be shaped so as to present the same appearance as the radiator sections, that is, the appearance of an ordinary skirting board. The panels may be made of sheet metal, 15 wood, papier maché, or any other suitable material. The individual radiator sections are in this case connected by pipes in the floor, as indicated by the dotted lines in Fig. 2.

20 The skirting board radiators according to my invention may of course be made in different sizes, that is, in different widths and heights, to suit the various requirements. Their height, for instance, may be made considerably greater than that of ordinary skirting boards, without interfering in any way with the good appearance of the room.

25 A molding strip J is suitably placed along the radiators, at their junction with the floor surface. The outside of the radiators and of the intervening panels I may be painted, if desired, to match the woodwork of the room.

30 In addition to the pipes F, the radiator sections are, of course, provided with suitable connections (not shown) for the ad-

mission of the heating medium such as steam, hot water, hot air, etc.

35 If desired, the radiator may suitably be insulated from the wall of the room by interposing between its rear wall and the wall of the room a layer of suitable packing material, say asbestos, felt, or the like, or instead I may simply leave an airspace between the wall of the room and the radiator. 40 45

Various modifications may be made without departing from the nature of my invention as set forth in the appended claims.

I claim as my invention:

1. In a heating arrangement for rooms and the like, radiator sections arranged alongside the walls of a room, and having their lower portions in the floor of the room, and pipes, also located in said floor, for connecting said radiator sections. 50 55

2. In a heating arrangement for rooms and the like, radiator sections arranged alongside the walls of the rooms and spaced from each other, said radiator sections being so formed as to present the appearance of 60 a skirting board, and panels arranged in the space intervening between said radiator sections, said panels being so formed that they will present the same appearance as said radiator sections. 65

In testimony whereof I affix my signature in presence of two witnesses.

HILDING LUBECK.
